UNITED STATES PATENT OFFICE.

JOHN LA FOLLETTE, OF PRINGLE, SOUTH DAKOTA.

MATCH-BOX.

1,287,702.

Specification of Letters Patent. Patented Dec. 17, 1918.

Application filed December 7, 1917. Serial No. 206,026.

To all whom it may concern:

Be it known that I, JOHN LA FOLLETTE, a citizen of the United States, residing at Pringle, in the county of Custer and State of South Dakota, have invented new and useful Improvements in Match-Boxes, of which the following is a specification.

This invention comprehends the provision of an attachment for the well known form of receptacles employed in carrying smoking tobacco, the attachment being in the nature of a match receptacle which is designed to keep matches in a dry and clean condition, and to further provide a convenience for the user by having the matches carried by the tobacco receptacle.

The invention is in the nature of an article of manufacture which can be readily and easily detached from one receptacle and quickly associated with a new receptacle of tobacco, although the invention may form an integral part of the tobacco receptacle without departing from the spirit of the invention.

One of the chief characteristics of the invention resides in the provision of means for securing the match container to the cover of the tobacco receptacle, the attaching means being susceptible of adjustment to be disengaged from the cover of the receptacle prior to the removal of the match receptacle from the latter, thus facilitating the removal of the match container from or its application to the cover of the receptacle as the occasion may require.

In carrying out the invention use is made of a pair of attaching plates carried by the opposed side walls of the match container, the attaching plates terminating to provide hooks adapted to engage beneath the longitudinal edges of the cover. One of the plates is formed with lugs slidably fitted in inclined slots in one side of the container, so that when the plate is adjusted in one direction upon the side of the container, it will be readily and easily separated from the cover to permit of the container as a unit to be subsequently disengaged therefrom.

The nature and advantages of the inven-

tion will be better understood when the following detail description is read in connection with the accompanying drawing, the invention residing in the construction, combination and arrangement of parts as claimed.

In the drawing forming part of this specification like numerals of reference indicate similar parts in the several views and wherein:

Figure 1 is a perspective view of the separate parts of the match container forming the subject matter of the invention.

Fig. 2 is a perspective view showing the match container associated with the lid of a tobacco receptacle, the lid being open.

Fig. 3 is an elevation of the tobacco receptacle showing the lid closed, and the match container opened to permit a match to be withdrawn therefrom.

Fig. 4 is a sectional view taken on line 4-4 of Fig. 3.

The device forming the subject matter of my invention essentially consists of the parts illustrated in Fig. 1, namely a casing substantially of oval contour in cross section, which is indicated at 10. The casing however can vary in cross sectional configuration without departing from the spirit of the invention. The casing is closed at one end as at 11, while the opposite end is open for the reception of the match container indicated generally at A. The match container is of corresponding cross sectional formation as the casing 10 excepting that the container 11' is provided with an opening or slot 12 in the top thereof to permit of the removal of matches when desired. The container 11' is also closed at both ends by means of walls 12', one of which constitutes a closure for the open end of the casing 10 when the parts are operatively associated, and which wall is provided with a flange 13 that embraces the adjacent end of the casing 10 when the container is in its full closed position. The body of the container 11' is cut away to provide a finger receiving opening as shown, to facilitate the removal of a match from the container subsequent to slid-

ing the latter outwardly of the casing in the manner shown in Fig. 3.

The device forming the subject matter of the invention is primarily intended for use 5 in conjunction with a metallic tobacco containing receptacle of the well known form now in use, and herein indicated at B, although it is to be understood that this is merely illustrative of one use of the invention, and that the latter may be used with 10 other types of receptacles when desired. The device is adapted to be mounted upon the hinged lid of the receptacle B, and may be permanently attached thereto, forming an 15 integral part thereof, or by preference the match container is detachably associated with the receptacle to permit of its ready separation from one receptacle and its quick association with another as the occasion may 20 require. While any suitable means may be utilized in detachably securing the device to the lid of the receptacle B, I preferably stamp from the bottom of the casing 10 a plurality of tongues 15 which depend from 25 the bottom of the casing at one side of the latter and adapted to embrace the adjacent longitudinal edge of the lid of the receptacle B. The tongues 15 are turned inwardly to provide terminal hooks 16 which 30 provides a proper connection between the attachment and the lid of the receptacle to prevent casual separation of the parts. An attaching plate 17 is carried by the casing 10 adjacent the opposite longitudinal edge 35 thereof, the plate being formed to provide terminal hooks 18 which depend below the bottom of the casing and adapted to engage beneath the free longitudinal edge of the lid of the receptacle as clearly illustrated in 40 Fig. 2. The plate 17 is stamped to provide inwardly disposed lugs 19 arranged to slide in inclined slots 20 and the purpose of this construction is to be presently set forth. When the plate 17 is adjusted in a direction 45 to bring the lugs 19 to the highest point of the slots 20, the terminal hooks 18 effectively engage the adjacent longitudinal edge of the lid of the receptacle B, and coöperate with hook terminals 16 to maintain the 50 match container immovably mounted upon the lid. However when it is desired to separate the attachment from the lid of the receptacle, this may be greatly facilitated by moving the plate in an opposite direction 55 to position the lugs 19 in the lowermost ends of the slots 20, during which movement of the plate the terminal hooks 18 will be moved away from the adjacent longitudinal edge of the cover or lid of the receptacle, 60 after which the attachment in its entirety may be easily removed. While the attachment may be constructed from any suitable material, it is preferred to construct the same from metal possessing the requisite

degree of resiliency to permit the tongue 15 65 and the terminal hooks to cling to the receptacle in a manner to effectively maintain the attachment immovably positioned thereon. When arranged in the manner described and shown, the lid of the tobacco 70 receptacle may be opened without any danger of the match container becoming casually deranged or separated from the lid. The container 11' is frictionally maintained in its closed position within the casing, thus 75 keeping the matches in a dry and clean condition, while the flange 13 serves as a finger grip to facilitate the removal of the container 11' from within the casing the required distance to permit of a match to be 80 removed from the container. One of the walls 12' of the container may be roughened to provide a striking surface for the match, or suitable material such as indicated at 16' may be secured to the wall for this 85 purpose.

While it is believed that from the foregoing description the nature and advantages of the invention will be readily apparent, I desire to have it understood that what is 90 herein shown and described is merely illustrative of the preferred embodiment, which is not to be considered restrictive, inasmuch as such changes in the construction and arrangement of parts may be resorted to when 95 desired as fall within the scope of what is claimed.

What is claimed is:—

1. The combination with a receptacle having a hinged lid, of a match carrier including a casing open at one end, and a match holder slidably fitted within said casing and having an end wall constituting a closure for the open end of said casing, and means carried by the said casing for detachably securing the latter to the lid of the receptacle. 100
2. A match carrier attachment for receptacles, including a casing closed at one end and open at the other, means for detachably 110 securing the casing upon the receptacle, a match holder slidably fitted within said casing, said holder having a slot in the top wall and a finger receiving opening at one side of said slot and communicating therewith, said holder including end walls, and one of said end walls constituting a closure for the casing and having a flange embracing the adjacent end of the casing. 115
3. The combination with a receptacle having a hinged lid, of a match container mounted upon the lid, hooks depending from one side of the container, a member adjustable upon the opposite side of the container, hooks depending from said member, said hooks engaging beneath the longitudinal edges of said lid, said member being adjustable to facilitate the removal of the 120
- 125

container from the lid or its association therewith.

4. The combination with a receptacle having a hinged lid of a match container mounted upon the lid, hooks depending from one side of the container, the opposite side of the container having inclined slots, a plate, lugs projecting from the plate and

movable within the slots whereby said plate may be lowered or elevated, hooks carried 10 by said plate, and all of said hooks adapted to engage beneath the opposite longitudinal edges of said lid as and for the purpose described.

In testimony whereof I affix my signature. 15
JOHN LA FOLLETTE.
